DESIGN FOR A CLOTHES AIRER

Alfred Edward Hutchings, Appledore, England

Application February 12, 1948, Serial No. 144,450
In Great Britain August 20, 1947

Term of patent 7 years

(Cl. D49—1)

To all whom it may concern:

Be it known that I, Alfred Edward Hutchings, a British subject, residing at Appledore, in the county of Devon, England, have invented a new, original, and ornamental Design for Clothes Airers, of which the following is a specification, reference being had to the accompanying drawing, forming part thereof.

Figure 1 is a perspective view of a clothes airer, showing my new design.

Fig. 2 is a rear elevational view thereof.

I claim:

The ornamental design for a clothes airer, as shown.

ALFRED EDWARD HUTCHINGS.
